COMBINATION SPACER AND FORM
SUPPORT

Hubert H. Echterling, East Chicago, Ind.

Application May 31, 1938, Serial No. 210,806

3 Claims. (Cl. 25—131.5)

This invention relates to an improved combination spacing and form supporting member which is especially adaptable for use with precast concrete joists.

One of the principal objects of the improved device of this invention resides in the provision of means for economically producing a device of the kind referred to for temporary use in maintaining precast concrete joists in desired spaced apart relation and vertical.

A still further important object of advantage is the provision of means for temporarily supporting floor form boards as a concrete floor is poured and at the same time maintaining the supporting joists vertical and in spaced apart relation.

Another and further object of importance and advantage resides in the provision of means for detachably securing the improved device to the lower bead of the joists with which the device is used.

Still another object of advantage and importance is the provision of means for quickly disengaging the securing hasp preparatory to removing the device from engagement with the joists.

A still further object of importance and advantage is the provision of means for preventing lateral tipping or tilting of the device when it is in engagement with the joists.

An additional object of advantage and importance resides in the provision of means for adjusting the length or depth of the improved device.

Additional objects of advantage and importance will become apparent as the following detailed description progresses, reference being had to the accompanying drawing wherein,

Fig. 1 is a front elevational view of a spacing and form supporting member which embodies the invention.

Fig. 2 is a top plan view thereof.

Fig. 3 is a sectional view, slightly enlarged, taken on line 3—3 of Fig. 1.

Fig. 4 is a vertical section, slightly enlarged, taken on line 4—4 of Fig. 1.

As shown in the drawing:

The reference numeral 10 indicates generally the horizontal form supporting portion of the improved device of this invention. In the preferred embodiment of the invention the form supporting member 10 is preferably constructed of two overlapping angle iron members as is best shown in Figs. 1 and 3.

Projecting downwardly from each outermost end of the horizontal member 10 is a vertical member 12. The vertical member 12 is preferably constructed of angle iron and may be an integral part of the horizontal member 10. It is to be noted that each end of the horizontal member 10 at its upper edge projects outwardly beyond the face of the vertical members 12 to form a contacting point adapted to engage the upper portion of a joist as is clearly shown in Fig. 1.

Adjustably secured to each vertical member 12 and extending therebelow is a vertical extension 14. A plurality of bolt receiving openings 16 are formed in each downwardly projecting extension 14, as is best shown in Fig. 1.

Provision is made for increasing or decreasing the length of the horizontal member 10 by a plurality of registering openings 18 in each overlapping angle iron member. The openings 18 are preferably round or relatively short slots. Long slots are preferably not employed as they tend to weaken the member 10.

From the foregoing it will be apparent that the supporting structure which comprises the members 10 and 12 is in reality two substantially L-shaped members adjustably joined together. However, it will be apparent that where adjustability of the device is not desired, the entire structure comprising the horizontal supporting member and the two vertical end members may be formed from a single piece of material.

Hingedly secured to the lower end of each vertical extension 14 is a securing hasp 20. The securing hasp 20 is preferably of L formation as is best shown in Fig. 1. When in operable position the hasp 20 extends outwardly from the vertical member 14 and thence upwardly as is indicated by the reference numeral 22. The upper edge 24 of the upwardly extending portion 22 of the hasp 20 is curled inwardly as is clearly shown in the drawing.

Curled outwardly from the upwardly extending portion 22 of the hasp 20 is a lug 26. The lug 26 provides a means for facilitating removal of the device from its association with precast concrete joists. A pinch-bar, hammer, or any other suitable tool may be employed on the lug 26 for moving the hasp into a releasing position.

Rigidly secured to the extension 14 or the vertical member 12 is a contact member 28. The contact member 28 is adapted to engage a joist 30 slightly above the lower bead thereof, as is best shown in Fig. 1.

The contact member 28 and the hasp 20 or 55

either of them tend to prevent accidental tilting or tipping of the device when in operable association with the joists.

5 Wing nuts 32 are preferably employed throughout for securing the parts of the device one to another.

10 It will be apparent from the foregoing that because the device is adapted to engage each joist at a point close to the top and also at the bottom there is here provided an efficient and inexpensive device for rigidly and securely holding joists vertical and in spaced relation and also for supporting floor form boards for concrete 15 floors and the like.

15 It will also be apparent from the foregoing that the improved device of this invention may be constructed to be used with conventional precast concrete joists positioned at predetermined intervals or may be made adjustable to accommodate 20 joists of various dimensions spaced at different intervals.

25 It will also be apparent to those skilled in the art to which the device appertains that numerous changes and alterations in construction and design may be made all without departing from the spirit or scope of this invention. Accordingly, it is understood that the patent granted hereon is not to be limited to the preferred embodiment here disclosed nor in any other manner except as necessitated by the terminology of the appended claims when given the range of equivalents to which they may be entitled.

I claim as my invention:

30 1. A combination spacer and form support comprising a substantially inverted U-shaped member, a contact member secured to each vertical portion of said U-shaped member intermediate the ends thereof, outwardly projecting contacting members at the upper end of each ver-

tical portion, said contacting member being adapted to engage the expanded upper portion of a joist, and an L-shaped hasp hingedly secured to the lower end of each vertical portion of said U-shaped member, the extremity of said 5 L-shaped hasp being turned to engage and grip the lower portion of a joist on the outside thereof in respect to the said U-shaped member.

2. A combination spacer and form support comprising a substantially inverted U-shaped 10 member, means for removably securing said U-shaped member to a pair of parallel joists, means engageable with the upper expanded portions of said joists for maintaining said joists vertical, a contact member secured to each vertical portion of said U-shaped member intermediate the ends thereof, and an L-shaped hasp hingedly secured to the lower end of each vertical portion of said U-shaped member, said L-shaped hasp being shaped to engage and grip a joist on the 15 side furthest from said U-shaped member.

20 3. A combination form support and joist spacing member comprising a horizontal member having a downwardly projecting portion at each end thereof, a plurality of joist contacting members on each downwardly projecting portion, said contacting members being adapted to engage a joist at the top, bottom, and intermediate portions thereof, and means at the bottom of each 25 downwardly projecting portion for removably securing said member to a pair of spaced joists, said means including hasp members, each of said hasp members having portions adapted to extend across the bottom of a joist and thence extending 30 upwardly and being adapted to engage and grip the vertical surface of the lower portion of said joist.
